UNITED STATES PATENT OFFICE.

WILLIAM JAMES LESTER, OF KEARNY, NEW JERSEY.

REDUCING OR REGULATING VALVE.

1,056,344.

Specification of Letters Patent. Patented Mar. 18, 1913.

Application filed July 18, 1912. Serial No. 709,195.

To all whom it may concern:
Be it known that I, WILLIAM J. LESTER, a citizen of the United States, residing at Kearny, in the county of Hudson and State of New Jersey, have invented certain new and useful Improvements in Reducing or Regulating Valves; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in valve mechanism; and the invention refers, more particularly, to a novel construction of reducing valve for controlling and regulating the volume of fluid passed therethrough.

The present invention has for its principal object to provide a simple, easily operated and effective construction of reducing valve-mechanism adapted to permit the passage therethrough of a stream of fluid, the volume of which may be regulated in various degrees from the maximum volume to the minimum volume easily and quickly, and in addition to such regulation the said valve-mechanism is constructed to shut-off the stream of fluid entirely when it is so desired.

Another object of the present invention is to provide a reducing valve-mechanism for controlling a stream of fluid passed therethrough which is so constructed as to readily indicate exteriorly of the valve-mechanism the proportionate degree of regulation of said stream of fluid between the given maximum and minimum volumes which said valve mechanism will pass.

Other objects of the present invention, not at this time more particularly enumerated, will be clearly understood from the following detailed description of my present invention.

With the various objects of the present invention in view, the said invention consists in the novel construction of reducing valve mechanism hereinafter set forth; and, furthermore, the invention consists in the novel arrangements and combinations of the various devices and parts as well as in the details of the construction thereof, all of which will be hereinafter more fully de-

scribed in the following specification, and then finally embodied in the clauses of the claims which are appended to and which form an essential part of this specification. 60

The invention is clearly illustrated in the accompanying drawings, in which:

Figure 1 is an elevation of one side of the novel construction of reducing valve mechanism made according to and embodying the principles of the present invention; Fig. 2 is an elevation of the opposite side thereof; Fig. 3 is a top or plan view thereof; and Fig. 4 is an end elevation of the same; Fig. 5 is a longitudinal vertical section of said novel construction of reducing valve mechanism, the same being illustrated in its closed or shut-off condition obstructing the passage of a stream of fluid therethrough; Fig. 6 is a similar vertical section of the same, 70 illustrating the valve mechanism in one of its opened positions; Fig. 7 is a side elevation of the regulating gate of said valve-mechanism, the same being removed from the valve-casing; and Figs. 8 and 9 are respectively transverse or horizontal sections of said regulating gate taken respectively on lines 8-8 and 9-9 in said Fig. 7.

Similar characters of reference are employed in all of the above described views to indicate corresponding parts. 85

Referring now to the said drawings, the reference-character 1 indicates the complete reducing or regulating valve mechanism made according to and embodying the principles of the present invention, the same comprising a valve casing 2 provided at each end with an interiorly screw-threaded opening 3 by means of which said valve-mechanism may be connected in a line of piping or the like. 90

Integrally formed in connection with said valve-casing 2, and preferably centrally located between its ends, are the walls 4 of a gate casing, the inner surface of said walls being tapered or inclined outwardly from the bottom to the top of said gate casing so as to provide a seat. The walls 4 of said gate-casing are provided with an upwardly extending part 5 which is exteriorly disposed with relation to said valve-casing 2. 100 This part 5 of said gate-casing is provided with an exteriorly disposed screw-thread 6. Connected by means of said screw-threads 6 to said gate-casing are the interiorly disposed screw-threads 7 of the flange or skirt 8 of a cap-member 9, which serves to close 110

the upper end of said gate-casing. Said cap-member 9 is provided with a centrally disposed perforation or opening 10, and upon its inner or under side with a socket-portion 11. Arranged within said gate-casing is a regulating gate-member 12, the walls 13 of which are tapered at their exterior surface so as to snugly engage the seat formed by the walls 4 of said gate-casing. Said regulating gate-member 12 is provided at its lower end with a chamber or well 14 which is bounded by its walls 13 and is closed at its upper end. Extending upwardly from the upper end wall of said gate-member 12 is a spindle-portion 15, which passes through said perforation or opening 10 of said cap-member 9 so as to be exteriorly presented above said cap-member. The upper free end of said spindle-portion 15 is provided with a reduced and squared-shank 16 upon which is secured, in any suitable manner, a handle-member 17. Surrounding the interiorly disposed portion of said spindle-portion 15 is a coil or compression spring 18, one end of which is seated within said socket-portion 11 of said cap-member 9, and the other end of which bears against the end wall of said gate-member 12 to maintain the same properly seated and operatively arranged in connection with said gate-casing. The walls 4 of said gate-casing are provided with an inlet passage or opening 19 and an outlet passage or opening 20, the latter being oppositely disposed with relation to the former, but being located in a horizontal plane below the horizontal plane of the former. The said inlet and outlet openings or passages respectively communicate with the respective open ends 3 of said valve-casing 2. The walls 13 of said gate-member 12 are provided with a plurality of intake perforations or openings 21, 21^a, 21^b, 21^c, and 21^d, and the same respectively decreasing in size or diameter, and extending around said wall 13 so as to lie in the plane of said inlet-opening or passage 19, with which they may be respectively registered so as to establish communication between the chamber or well 14 of said gate-member and one open end of said valve-casing 2. In like manner said walls 13 of said gate-member 12 are further provided with a plurality of exit perforations or openings 22, 22^a, 22^b, 22^c, and 22^d, and the same respectively decreasing in size or diameter, and extending around said wall 13 so as to lie in the plane of said outlet opening or passage 20, with which they may be respectively registered so as to establish communication between said wall or chamber 14 of said gate-member and the opposite open end of said valve-casing 2. The respective series of intake and exit perforations or openings above described are so disposed with relation to each other that the openings or per-

forations of the same size in said respective series will respectively register with the inlet and outlet passages or openings 19 and 20 when said gate-member 12 is rotated, and in this manner, as will be clearly understood, the volume of the stream of fluid passed through the valve-mechanism may be variously controlled between a minimum and maximum volume, according to the size of the selected opening of said series of perforations or openings registered with the respective inlet and outlet passages 19 and 20. In order to permit the selection of any of said series of perforations or openings in said gate-member 12 for registration with said inlet and outlet passages 19 and 20, and to afford a visible means, exterior of said valve casing 2, whereby the position of said gate-member may be properly indicated when such perforations or openings are so properly registered, the exterior surface of said flange or skirt 8 of said cap-member 9 is provided with a series of properly spaced and numbered, or otherwise indicated, graduations 23, one for each pair of perforations in said respective series of intake and exit perforations or openings, and an indicated graduation 24 for indicating the shut-off position of said gate-member 12, and connected with said handle-member 17, which operates or turns said gate-member 12, is an outwardly projecting arm 25 provided with a downwardly turned indicating pointer 26 which when registered with any of said graduations indicates the position of said gate-member 12. The said walls 13 of said gate-member 12 are provided with dead-spaces 27 and 27^a, i. e. unperforated, which when respectively registered with the respective inlet and outlet passages 19 and 20 block or shut-off the passage of the fluid through said regulating gate-member as indicated in Fig. 5 of the drawings.

From the above description of the present invention it will be evident that the present invention provides a very simple reducing or regulating valve-mechanism, which affords a quick and easy means for reducing or regulating the volume of fluid desired to be passed through said valve, or for shutting-off entirely the passage of fluid therethrough, and owing to the convenient indicating devices connected with said valve-mechanism it may be quickly and easily ascertained, by a glance at the exterior of said valve, in just what position the regulating gate-member is set at any given time, or in the operation of the gate-member itself.

I am aware that some changes may be made in the various details and arrangement of the devices and parts of the present invention without departing from the scope thereof. Hence, I do not limit my invention to the exact arrangements and combinations

of the various devices and parts as herein set forth, and as illustrated in the accompanying drawings, nor do I confine myself to the exact details of the construction of 5 the said parts.

I claim:—

1. In a device of the kind described, a valve casing having open ends, a gate-casing formed in connection with said valve-casing, said gate-casing being provided with an inlet passage and an outlet passage, a rotatable gate-member mounted within said gate-casing, said gate-member being provided with a series of variously sized intake 10 perforations adapted to be registered with said inlet passage and a series of variously sized exit perforations adapted to be registered with said outlet-passage, intake perforations and exit perforations of corresponding size being adapted to be selectively registered respectively with said inlet passage and said outlet passage of said gate-casing, said gate-member being provided with a chamber with which said respective 15 series of perforations communicate, and means exteriorly disposed of said valve casing and said gate-casing for rotating said gate-member.

2. In a device of the kind described, a valve-casing having open ends, a gate-casing formed in connection with said valve-casing, said gate-casing being provided with an inlet passage and an outlet passage, a rotatable gate-member mounted within said gate-casing, said gate-member being provided with a series of variously sized intake perforations adapted to be registered with said inlet passage and a series of variously sized exit perforations adapted to be registered 20 with said outlet-passage, intake perforations and exit perforations of corresponding size being adapted to be selectively registered respectively with said inlet passage and said outlet passage of said gate-casing, said gate-member being provided with a chamber with which said respective series of perforations communicate, a handle-member, means for connecting said handle-member with said gate-member, and means with which said 25 handle-member may be registered to indicate the regulated position of said gate-member.

3. In a device of the kind described, a valve-casing having open ends, a gate-casing formed in connection with said valve-casing, an exteriorly projecting portion connected with said gate-casing the same being exteriorly threaded, a cap-member interiorly threaded to screw upon said exteriorly projecting portion of said gate-casing, said cap-member being provided with a centrally disposed opening, said gate-casing being provided with an inlet passage on one side and an outlet-passage on the opposite side 30 each communicating with the interior of

said valve-casing, a rotatable gate-member provided with an interior chamber, said gate-member being seated within said gate-casing, a spindle-member extending upwardly from said gate-casing and projecting through said opening of said cap-member, a coil-spring arranged about said spindle-member between said cap-member and said gate-member, said gate-member being provided with a series of variously sized intake perforations adapted to be selectively registered with said inlet passage, a series of variously sized exit perforations adapted to be selectively registered with said outlet passage simultaneously with said first-mentioned series, said respective series of perforations communicating with said chamber of said gate-valve, and means connected with said spindle-member for rotating said gate-member. 70

4. In a device of the kind described, a valve-casing having open ends, a gate-casing formed in connection with said valve-casing, an exteriorly projecting portion connected with said gate-casing the same being exteriorly threaded, a cap-member interiorly threaded to screw upon said exteriorly projecting portion of said gate-casing, said cap-member being provided with a centrally disposed opening, said gate-casing being provided with an inlet passage on one side and an outlet-passage on the opposite side each communicating with the interior of said valve-casing, a rotatable gate-member provided with an interior chamber, said gate-member being seated within said gate-casing, a spindle-member extending upwardly from said gate-casing and projecting through said opening of said cap-member, a coil-spring arranged about said spindle-member between said cap-member and said gate-member, said gate-member being provided with a series of variously sized intake perforations adapted to be selectively registered with said inlet passage and a series of variously sized exit perforations adapted to be selectively registered with said outlet passage simultaneously with said first mentioned series, said respective series of perforations communicating with said chamber of said gate-valve, a handle-member connected with said spindle-member for rotating said gate-member, and means with which said handle-member may be registered to indicate the regulated position of said gate-member. 90

5. In a device of the kind described, a valve-casing having open ends, a gate-casing formed in connection with said valve-casing, an exteriorly projecting portion connected with said gate-casing the same being exteriorly threaded, a cap-member interiorly threaded to screw upon said exteriorly projecting portion of said gate-casing, said cap-member being provided with a centrally dis- 100

posed opening, said gate-casing being provided with an inlet passage on one side and an outlet passage on the opposite side each communicating with the interior of said 5 valve-casing, a rotatable gate-member provided with an interior chamber, said gate-member being seated within said gate-casing, a spindle-member extending upwardly from said gate-casing and projecting 10 through said opening of said cap-member, a coil-spring arranged about said spindle-member between said cap-member and said gate-member, said gate-member being provided with a series of variously sized intake 15 perforations adapted to be selectively registered with said inlet passage and a series of variously sized exit perforations adapted to be selectively registered with said outlet passage simultaneously with said, first-mentioned series, said respective series of perforations communicating with said chamber of said gate-member, a handle-member connected with said spindle-member for rotating said gate-member, a series of graduations 20 arranged upon said cap-member, and a pointer-portion connected with said handle-member adapted to register selectively with said graduations to indicate the regulated position of said gate-member.

30 6. In a device of the kind described, a valve-casing, a gate-casing, a gate-member

rotatably seated within said gate-casing, said gate-casing being provided with inlet and outlet openings, said gate-member being provided with graded intake and exit openings adapted to be selectively registered with said inlet and outlet openings of said gate-casing, a perforate cap-piece connected with the exterior end of said gate-casing, a spindle-portion connected with said gate-member and projecting through said perforate cap-member, a compression spring arranged around said spindle-member between said gate-member and said cap-piece adapted to maintain the said gate-member in proper seated position within said gate-casing, a handle-member connected with the outer end of said spindle-member, said cap-piece being exteriorly provided with a series of properly spaced and indicated graduations, and an indicating-pointer connected with said handle-member adapted to register with said graduations to indicate the regulated position of said gate-member.

In testimony, that I claim the invention set forth above I have hereunto set my hand this ninth day of July, 1912.

WILLIAM JAMES LESTER.
